United States Patent Office

Des. 179,824
Patented Mar. 5, 1957

179,824

ELEVATED TANK

Rolland G. Sturm, Auburn, Ala., assignor to Graver Tank
& Mfg. Co., Inc., East Chicago, Ind., a corporation of Delaware

Application August 25, 1955, Serial No. 37,667

Term of patent 14 years

I claim:

The ornamental design for an elevated tank as shown.
